(57) **CLAIM**

The ornamental design for an exercise weight plate, as shown and described.

DESCRIPTION

FIG. 1 is a front perspective view of an exercise weight plate, showing my new design.

FIG. 2 is a front view thereof.

FIG. 3 is a rear view thereof.

FIGS. 4 and 5 are opposing side views thereof.

FIG. 6 is a top view thereof; and,

FIG. 7 is a bottom view thereof.

The broken lines represent portions of the exercise weight plate that are shown for illustrative purposes only and form no part of the claimed design.

1 Claim, 5 Drawing Sheets
